APPARATUS FOR TESTING METAL CONTAINERS

John F. Werder, Lakewood, Ohio, assignor of
one-half to Edmund Rogers, South Euclid,
Ohio

Application January 10, 1931, Serial No. 507,930

3 Claims. (Cl. 73—51)

This invention relates to a device for testing containers which are intended to withstand substantial internal pressure.

Although capable of any use to which such container may be put, yet in the present instance, the container may be formed of metal or any other suitable material and is used for the packaging of a gas-charged liquid, as for instance, a lubricant for automobiles. In the present case, 10 there is employed a metal container which may be constructed of tin plate and which includes the familiar longitudinal seam as well as the two head seams. This container is intended to withstand substantial internal pressure for the discharge of the lubricant therefrom. As a precautionary and preliminary measure, that is, prior to the charging of the container with the gas-charged liquid, applicant has herein provided a convenient form of apparatus by which 15 the container may be subjected to substantial internal pressure corresponding at least to the pressure of the gas-charged liquid with which it will later be filled, so that any leaks can be discovered and repaired. Otherwise, such leaks 20 would mean the loss of the contents of the container.

It is therefore the object of the present invention to devise an apparatus by which the containers may be tested and any leaks discovered 30 prior to the filling of the same with the gas-charged liquid.

A further object consists in devising such an apparatus in which the containers, while being subjected to such internal pressure, will be removed at a safe distance from the normal position 35 of the hand of the operator so as to prevent any injury which might result from the explosion of the container under such pressure.

A still further object consists in devising such an apparatus of comparatively simple form and capable of convenient and speedy operation together with a conveniently arranged means for indicating any leak in the container.

Other objects will appear from the following 45 description and claims when considered together with the accompanying drawing.

Fig. 1 shows my improved form of apparatus in elevation with a part thereof shown in section; Fig. 2 is a sectional detail view of the detachable connecting means between the testing apparatus and the container.

It is to be understood that the present form 55 of disclosure is merely for purposes of illustration and that there may be devised various modifica-

tions without departing from the spirit of the present invention as herein claimed.

The metal container 1 is provided in its one end with a valve casing 2 which is adapted for screw-thread engagement with a valve member 5 for opening and closing the passage therethrough and for the discharge of the contents through the outlet 3. Connected to the valve casing and extending longitudinally of the container is the siphon tube 4. During the testing operation, the valve member is removed from the casing 2 and in lieu thereof, there is connected with the valve casing by screw-thread engagement the connection 5 at the lower end of the air tube 6, that is, the container is connected to the lower end of the tube 6 by means of the connection just referred to. The tube 6 extends transversely through the main air supply pipe line 7 and has air-tight connection therewith by means of the sleeves 8 through which the tube 6 is adapted to be adjusted vertically by sliding the same up and down therethrough. The tube 6 in each case is closed at its upper end and is provided with an aperture 9 extending transversely therethrough so as to provide communication between the main pipe line 7 and the tube 6 when in lowered position, that is, when the aperture 9 is in position within the tube 7. The sleeves 8 through which the tube 6 is arranged for up and down adjustment, are provided upon the pipe connections 7a 30 between the sections 7 of the main supply line. Upon each pipe 6, there is fixedly mounted a handle 10 at proper elevation for raising and lowering the tube 6 so as to bring the aperture 9 into either operative or inoperative position with 35 respect to the supply line 7 and at the same time to locate the container 1 within the water-filled container 11, or to remove the same therefrom. Any suitable means of air pressure supply may be connected at the end 7b of the line 7 and there 40 is interposed a gauge 12 to indicate the degree of pressure. Any number of slides tubes 6 may be provided upon the supply line 7, and there will be provided also a corresponding number of water-filled compartments into which the containers upon the lower ends of the tubes 6 may be projected for the testing operation.

When the tube 6 in each case is in raised position, the aperture 9 is out of communication with the supply line 7 and the lower end of the tube 6 50 is elevated sufficiently above the level of the water in the container 11 to permit attachment of the container thereto by screw-thread engagement, as already indicated. The tube 6 is raised to such elevated position by means of the handle 10 which 55

upon striking the lower sleeve 8, will limit the upward movement thereof. Then when the container 1 has been attached in such manner to the lower end of the tube 6, it will be lowered by means of the handle 10 so as to project the container into the water so as to become completely submerged thereby and at the same time to bring the aperture 9 within the pipe line 7 for supply of air pressure therethrough to the tube 6 and into the container 1, that is, as soon as the container has been completely submerged. These parts are so constructed and arranged, however, that the aperture 9 will not be brought into communicating position within the pipe line 7 until the container 1 has been lowered to such an extent that it is completely submerged within the water-filled container 11. No other operation is necessary to communicate the air pressure to the container 1, as such pressure at all times is available in the pipe line 7. Only a brief interval of time is required for the application of the pressure through the tube 6 to the container 1 in order to determine whether there are any leaks in the container or in the valve connections. Any such leaks will be indicated by the bubbling of the water as the air escapes from the container. As soon as the operator has determined the presence or absence of leaks within the container, the tube 6 will be elevated by means of the handle 10 so as to permit the removal of the container 1 therefrom and the attachment of another container to be subjected to the same test. Any leak which has been discovered may then be repaired. The tube 6 in each case is of such length that the container upon being subjected to such internal pressure is removed from the point of the handle 10 to such an extent that there is precluded any danger to the hand of the operator as might otherwise be caused as a result of the explosion of the container by such pressure.

Thus, I have devised a comparatively simple and convenient form of apparatus for the containers which may be attached, tested, and removed at a comparatively high rate of speed and in which the operation is without danger to the operator because of the automatic positioning of the containers at a comparatively remote point with respect to the hand of the operator during the application of such pressure to the container.

What I claim is:

1. Testing apparatus for a metal container of the type having a valve body, said apparatus comprising a pressure supply line, extendable tubular

means affording communication between said pressure supply line and the valve body and container, means for connecting said tubular means with said valve body, said tubular means having a port so located that when said tubular means is in withdrawn position, said port is open to the outside atmosphere, and when said tubular means is in extended position, said port is in communication with said pressure supply line so as to permit application of pressure to the container, whereby successive containers may be applied to and removed from said tubular means when in withdrawn position and the container may be subjected to pressure only when in extended position, said parts being so constructed and arranged that the container will be substantially removed from the normal manipulating position of the hands of the operator during the application of pressure to the container. 5 10 15

2. Testing apparatus for metal containers, comprising a pressure supply line, tubular means adjustable along a straight line for supporting and extensibly connecting the container to said pressure supply line, a valve in said connecting means for controlling the supply of pressure, 25 means for containing a liquid into which the container may be projected when said extensible means is in longitudinally extended position for indicating leaks in the container, and means whereby said valve will be automatically rendered 30 effective for transmission of pressure when said container is projected along a straight line fully into said liquid and will be rendered effective for release of such pressure from the container upon said container being withdrawn therefrom, thereby affording protection to the operator. 35

3. Testing apparatus for metal containers, comprising a pressure supply line, tubular means adjustable along a straight line for supporting and extensibly connecting a container to said pressure supply line, said extensible means having a lateral opening therethrough for establishing communication between said pressure supply line and the container when said extensible means is in longitudinally extended position, and for 45 establishing discharge communication between the container and the outside atmosphere when said extensible means is in withdrawn position, whereby successive containers may be applied to and removed from said extensible means when 50 in withdrawn position and the container will be subjected to pressure only when said extensible means is in extended position, thereby affording protection to the operator.
